UNITED STATES PATENT OFFICE.

ERIK MAGNUSEN, OF PROVIDENCE, RHODE ISLAND, ASSIGNOR TO GORHAM MFG. CO., OF PROVIDENCE, RHODE ISLAND.

DESIGN FOR A CANDLESTICK.

Application filed March 21, 1927. Serial No. 21,242. Term of patent 14 years.

To all whom it may concern:

Be it known that I, ERIK MAGNUSEN, a citizen of the United States, residing at Providence, in the county of Providence and State of Rhode Island, have invented new and original and ornamental Design for a Candlestick, of which the following is a specification, reference being had to the accompanying drawings, forming part thereof.

Figure 1 is a perspective view of the candlestick;

Figure 2 is a sectional view of one half of the candlestick;

Figure 3 is a section on the line 3—3; Figure 4 is a detailed plan view of the flange member shown near the base of Figure 1 and forming a portion of the design illustrated therein, and

Figure 5 is a plan view of the top of the candlestick.

I claim:

The ornamental design for a candlestick, as shown.

In testimony whereof I have signed my name to this specification.

ERIK MAGNUSEN.
